(57) **CLAIM**

The ornamental design for a blood glucose meter as shown and described.

DESCRIPTION

1. Blood glucose meter

1.1 : Perspective

1.2 : Perspective

1.3 : Front

1.4 : Back

1.5 : Left

1.6 : Right

1.7 : Top

1.8 : Bottom

Fig. 1.1 is a front, right, and bottom perspective view of a blood glucose meter showing our new design; fig. 1.2 is a rear and right side perspective view thereof; fig. 1.3 is a front elevation view thereof; fig. 1.4 is a rear elevation view thereof; fig. 1.5 is a left-side elevation view thereof; fig. 1.6 is a right-side elevation view thereof; fig. 1.7 is a top view thereof; and fig. 1.8 is a bottom view thereof.

The broken lines in the drawings represents portions of the blood glucose meter that form no part of the claimed design.

1 Claim, 8 Drawing Sheets
